UNITED STATES PATENT OFFICE.

OTTILIE KUEHNER, OF PROVIDENCE, RHODE ISLAND.

SHOE-LACE CAP.

990,991.

Specification of Letters Patent.

Patented May 2, 1911.

Application filed December 17, 1910. Serial No. 597,787.

To all whom it may concern:

Be it known that I, OTTILIE KUEHNER, a citizen of the United States, and resident of Providence, in the county of Providence and 5 State of Rhode Island, have invented certain new and useful Improvements in Shoe-Lace Caps, of which the following is a specification.

This invention relates to a protecting and 10 ornamental cap or covering for shoe lacings, its object being to provide such a covering and construct the same of metal or other suitable material, the same to be handsome and attractive in appearance and to also 15 serve as a shoe ornament, the device being designed to be attached to that portion of the shoe lacing which extends across between the shoe eyelets or lacing hooks. The cap in addition to covering and protecting the lac- 20 ings against wear also may be employed as a covering for the lacing hook, to prevent ladies' dresses, or other articles, catching in the hooks.

A further object is to provide simple and 25 effective means whereby the device may be readily attached to and detached from the shoe lacing.

With these and other objects in view, the 30 invention consists of certain novel features of construction, as will be more fully described and particularly pointed out in the appended claims.

In the accompanying drawings: Figure 1— illustrates a shoe with my improved ornamental and protecting cap attached to the shoe lacing. Fig. 2— is an enlarged cross sectional view illustrating my device as attached to the lacing which extends between two eyelets in the shoe upper, said device ex- 40 tending over and covering the eyelets. Fig. 3— is a cross sectional view similar to Fig. 2, in which the device is illustrated as covering the lacing hooks in the shoe upper. Fig. 4— is a sectional end elevation of the cap. 45 Fig. 5— is a plan view showing the underside of the cap and its attaching members. Fig. 6— is a transverse section of the cap through one of the hook-shaped arms.

Referring to the drawings, 1 designates 50 the body portion of my protecting and ornamental cap. The same may be constructed of any suitable material but is preferably struck up out of sheet metal having a round- 55 ing or oval contour in cross section, whose side walls 2 and end walls 3 are preferably turned downward forming a body or shell

which is concaved or hollow on its under- 60 side, said concaved or hollow portion being primarily for the purpose of receiving the shoe lacing 5 therein, covering the same, and 65 permitting it to pass therethrough from one eyelet or lace engaging member 6 to the other in each side of the shoe upper 7, without being exposed to view. This body portion is preferably made on a slight curve from end 65 to end so as to conform to the rounding contour of the instep over which the device is worn. Any suitable means may be attached to this body portion for receiving the shoe lacing, such as eyelet hooks 4—4 see Fig. 4, 70 but I preferably employ a pair of hook shape arms 8 one of which is illustrated in Fig. 6, said arms being formed integral with the edge of the cup body and bent under to engage the lace. These arms may be passed 75 around the lacing 5, thus obviating the necessity of unlacing the shoe in order to attach the device to the lacing. These devices in addition to serving as a cover for the lacings protecting them against the con- 80 stant abrasive wear of a lady's skirt while walking, also serve as an ornament and may be made to add considerably to the neatness of appearance of the boots or shoes on which they are worn.

85 In practice it is found that lacing hooks are not applied to ladies' shoes owing to the fact that the dresses catch therein. To obviate this difficulty the ends of my protecting device may extend over and cover these 90 unsightly hooks, effectually preventing the dress material from catching therein.

In addition to their utility these devices are very neat and attractive in appearance, simple to attach and detach, and cause the 95 laced-up portion of the shoe to present a uniform appearance.

I claim:

1. A shoe lace cap comprising an elongated body having its outer edges turned 100 downward forming a shell concaved on its underside for the reception of the shoe lace, said body being adapted to extend across the opening in the shoe upper from one eyelet to another and cover the lacing between 105 said eyelets, and means on the underside of said body whereby the same may be readily attached to the shoe lacing.

2. A shoe lace cap comprising an elongated body having its outer edges turned 110 downward forming a shell concaved on its under side for the reception of the shoe lace,

said body being adapted to extend across the opening in the shoe upper from one eyelet to another and cover the lacing between said eyelets, and one or more hook-shaped 5 members on the underside of said body whereby the same may be readily attached to and detached from the shoe lacing.

In testimony whereof I affix my signature in presence of two witnesses.

OTTILIE KUEHNER.
